UNITED STATES PATENT OFFICE

2,506,897

VACUUM CLEANER SUPPORT

James W. Sheker, Fort Dodge, Iowa

Application July 11, 1946, Serial No. 682,814

4 Claims. (Cl. 248—304)

1

This invention relates to a supporting means for a vacuum cleaner of the cylinder type and is an improvement over the construction embodied in my prior patent issued May 18, 1943, No. 2,319,638.

An object of this invention is to provide an improved vacuum cleaner support whereby the cleaner may be suspended from the wall or vertical support with the cylinder in depending relation and with the hose coupled to the cleaner and wrapped around a portion of the support so that the attachment at the end of the hose may be used for various purposes with the cleaner in suspended relation.

Another object of this invention is to provide a support of this kind which is made substantially in one piece and can be made of a size to readily fit into the carton or case of the cleaner so that the support may be shipped with and sold with the cleaner.

A further object of this invention is to provide a device of this kind which is of simple construction so that it can be manufactured at small cost and sold either as a separate support item for use with a cleaner or may be sold with the cleaner.

With the above and other objects in view, my invention consists in the arrangement, combination and details of construction disclosed in the drawings and specification, and then more particularly pointed out in the appended claims.

In the drawings,

Figure 1 is a detail front elevation of a supporting device constructed according to an embodiment of this invention.

Figure 2 is a detail side elevation of the device.

Referring to the drawing, the numeral 10 designates an elongated supporting bar which is formed at its upper end with a loop or eye 11 for receiving a supporting hook or other element to suspend the bar 10 in a substantially vertical position. The bar 10 at its lower end is flattened or broadened as indicated at 13 and a cleaner supporting element generally designated as 12 is fixed to the flattened portion 13. The cleaner supporting element 12 includes a pair of outwardly extending arms 14 and 15 which are integral with each other and the inner ends of the arms 14, 15 are bent upwardly in substantially U-shape as indicated at 16, 17.

The U-shaped upwardly extending integral portions 16, 17 are adapted to be welded or otherwise firmly secured to the enlarged lower end portion 13 of the bar 10. The outer portions of the supporting arms 14, 15 are bent downwardly

2

and outwardly as indicated at 18, 19 and then terminate in supporting hooks 20, 21 having eyes 22, 23. The hooks 20, 21 are adapted to receive the eyes of runners 24, 25 of the cylinder type vacuum cleaner designated as 26 and shown in dotted lines in the drawing.

In order to provide means for supporting the hose which is attached to the cap 27 of the cleaner 26, I have provided a supporting bracket or saddle generally designated as 28. The bracket or saddle 28 includes a pair of oppositely extending supporting arms 29, 30, which have formed integral with the outer ends thereof U-shaped members 31, 32. The U-shaped members 31, 32 are connected together by means of a connecting bar 33 which connects the outer legs of the U-shaped members 31, 32 together.

The hose H which is connected to the cap 27, is adapted to be looped about the bracket or saddle 28 as shown in dotted lines in Figure 1. The supporting arms 29, 30, have formed integral therewith upwardly extending bars 34, 35, which are welded or otherwise firmly fixed to a flattened intermediate portion 36 which is formed in the supporting bar 10. The flattened portion 36 is disposed at right angles to the flattened or enlarged portion 13 at the lower end of the bar 10.

The arm 34 has extending from the upper end thereof an outwardly extending arm 37, and the arm 37 has extending forwardly therefrom a supporting bar 38 terminating in a hook or loop 39. The arm 35 has extending outwardly at right angles thereto a supporting bar or arm 40 which also has extending forwardly from the outer end thereof a supporting arm or bar 41, similar to the bar or arm 38.

A hook or loop 42 is formed integral with the outer end of the supporting arm 41 and extends upwardly therefrom so that if desired the suction nozzle N connected to the hose H may be supported between the arms 38 and 41. The arms 38 and 41 may also have the electric conductor of the cleaner 26 looped thereabout.

With the construction of the device hereinbefore described, this device may be made as a single unit which may be of such length as to engage within the carton or case of the cleaner 26 so that for new cleaners the support may be sold therewith. The material of which this support is constructed may be made of relatively heavy round, square or otherwise shaped wire or bar which has sufficient rigidity to retain its predetermined shape and to support the cleaner and other elements associated with the cleaner.

I do not mean to confine myself to the exact details of construction herein disclosed, but claim all variations falling within the purview of the appended claims.

What I claim is:

1. An article support comprising an elongated vertical bar, an article supporting element fixed on the lower end of said bar comprising a member bent upon itself to form a pair of article supporting hooks on opposite sides of said bar spaced outwardly therefrom, an article supporting saddle member fixed on said bar above said article supporting element comprising a member bent upon itself to form a pair of forwardly extending and upwardly opening U-shaped members on opposite sides of said bar, a pair of intermediate arms on said saddle member fixed to said bar, and a pair of horizontally spaced apart hook members above said U-shaped members.

2. A vacuum cleaner support comprising an elongated vertical bar having a loop at its upper end, a length of wire bent to form a central shank welded to the lower end portion of the bar and laterally outwardly and downwardly extending arms with horizontal portions having upturned terminal coils, a length of wire bent to form oppositely outwardly extending horizontal arms welded centrally to the bar below its upper end and formed at their outer ends with depending forwardly and upwardly bent hooks having a transverse horizontal connection portion therebetween, and an upper horizontal portion welded centrally to the bar above the second arms with oppositely outwardly extending horizontal arms having horizontal forwardly bent end portions terminating in upturned coils spaced apart inwardly of and above the first coils.

3. A vacuum cleaner support comprising an elongated vertical bar having an eye at its upper end to suspend the bar from a fixed support and

having upper and lower flattened portions at its upper and lower portions, a length of wire rebent intermediately to form an upwardly extending attaching shank welded to the lower flattened portion and oppositely outwardly extending arms terminating in horizontal portions with hooked ends, a length of wire rebent upon itself to form a pair of oppositely outwardly extending horizontal arms bent downwardly and forwardly to form hooks open at the top and an intermediate connecting portion therebetween and spaced vertical portions welded to the upper flattened portion and having their upper ends bent horizontally outwardly in opposite directions and then forwardly and terminating in upwardly hooked ends.

4. A vacuum cleaner support comprising a unitary elongated vertical bar having an eye at its upper end to suspend the bar from a fixed support, and hook means formed at its lower end to provide a support with an intermediate section positioned therebetween, and having a plate-like portion associated with said intermediate section, and a bracket welded to said plate-like portion, said bracket having extensions disposed at right angles relative to said vertical bar and extended upwardly to form a saddle portion laterally of said bar, and a member extending downwardly relative to said plate-like portion to form a hook portion.
